UNITED STATES PATENT OFFICE.

HECTOR G. EVANS, OF PITTSBURGH, PENNSYLVANIA, ASSIGNOR OF ONE-HALF TO
JAMES F. EWING, OF PITTSBURGH, PENNSYLVANIA.

RAIL-JOINT.

1,090,699.

Specification of Letters Patent. Patented Mar. 17, 1914.

Application filed December 29, 1913. Serial No. 809,292.

To all whom it may concern:

Be it known that I, HECTOR G. EVANS, a citizen of the United States of America, residing at Pittsburgh, in the county of 5 Allegheny and State of Pennsylvania, have invented certain new and useful Improvements in Rail-Joints, of which the following is a specification, reference being had therein to the accompanying drawing.

10 This invention relates to rail joints, and has for its object to provide means, in a manner as hereinafter set forth, for connecting the opposing ends of a pair of track rails together to form practically a continuous rail to prevent lateral and longitudinal movement with respect to each other and to further provide for the contraction and expansion of the rails when connected together.

15 Further objects of the invention are to provide a rail joint which is simple in its construction and arrangement, unusually strong and durable, efficient in its use, readily set up for connecting the opposing ends 25 of a pair of track rails together, having the intermediate portion thereof forming a continuation of the opposing ends of the rails, readily set up and comparatively inexpensive to manufacture.

20 With the foregoing and other objects in view, the invention consists of the novel construction, combination and arrangement of parts as hereinafter more specifically described and illustrated in the accompanying 35 drawings, wherein is shown an embodiment of the invention, but it is to be understood that changes, variations and modifications can be resorted to which come within the scope of the claims hereunto appended.

30 In the drawings wherein like reference characters denote corresponding parts throughout the several views: Figure 1 is a sectional plan of a rail joint in accordance 45 with this invention, Fig. 2 is a section on line X—X Fig. 1, looking in the direction of the arrows, and Fig. 3 is a section on line Y—Y looking in the direction of the arrows.

40 Referring to the drawings in detail, 4 and 5 denote a pair of track rails which when set up have their opposing ends spaced from each other, the said opposing ends being connected together by a joint in accordance 55 with this invention, the joint having

a part thereof interposed between and forming a continuation of said ends.

Interposed between the opposing ends of the rails 4 and 5 is a bridge member consisting of a base 6, the intermediate or web 60 portion 7 and a head 8, the latter being of the same contour as the head 9 of one of the track rails. One side of the intermediate portion or web 7 forms a continuation of one side of the base 6 and head 8 65 and is flush at its upper portion with the side 10 of the head 9 and at its lower portion flush with the side 11 of the base 6. The intermediate portion 7 of bridge member is interposed between the rails 4 and 5, 70 projects between the web 12 of the track rails as indicated at 13 and the said projecting side has formed integral therewith a stepped projection 14 and a pair of tongues 15, each of which has its outer portion provided with an opening 17. The projection 14 is of the same height as the intermediate portion 7, while the tongues 15 are arranged centrally with respect to the head 8 and base 6. 80

Formed integral with the bridge member are a pair of oppositely extending fish plates 18 and 19, which are arranged at one side of the webs 12 of the rails 4, 5, and extend from the bases 20 to the heads 9. The fish 85 plates 18 and 19, are spaced slightly from the webs 12 as indicated at 21. Formed integral with the extension 14 is a longitudinally disposed fish plate 22 which is arranged at the side of the web 12 of the rail 90 4 and opposite the fish plate 19. The fish plate 22 extends from the base 20 to the head 9 of the rail 4.

The reference character 23 denotes a fish plate which is shouldered at one end as at 95 24 for engagement with the stepped extension 14, and the said fish plate 23 is furthermore provided with openings 25 for the passage of the tongues 15. The tongues 15 are of a length to project from the fish 100 plate 23 so that wedges 16 can be forced in the opening 17 and engage the fish plate 23 whereby the latter is detachably connected to the intermediate portion 7 of the bridge member. The fish plate 23 extends at one 105 side of the web 12 of the rail 5 and is arranged opposite the fish plate 18. The fish plate 23 extends from the base 20 to the head 9 of the rail 5 and from the base 6 to the head 8 of the bridge piece. The lower 110

edge of the fish plate 23 is provided with a flange 25 whereby said lower portion will be flush with the edge of the base 6 of the bridge piece. The fish plate 22 as well as 5 the fish plate 23 is spaced from the webs 12 of the rails 4 and 5 as at 26. The fish plates have their outer sides beveled whereby they will gradually decrease in width toward the heads 9 of the rails 4 and 5.

- 10 When setting up the joint, the bridge piece is mounted in position upon a tie and secured to the latter in any suitable manner, after which the rail 4 is slid under the fish plates 19 and 22 and positioned against one 15 side of the base 6 of the bridge piece. The rail 4 is then spiked down. The rail 5 is then slid under the fish plate 18 against the opposite side of the base 6 of the bridge piece and the rail 5 is then spiked down. The 20 fish plate 23 is then mounted in position and connected to the bridge piece.

What I claim is:—

1. A rail joint comprising a bridge piece having formed integral at one side thereof 25 a pair of longitudinally extending spaced parallel fish plates and at its other side with a longitudinally extending integral fish plate, said bridge piece formed with laterally projecting tongues, a fish plate mounted upon said tongues and arranged parallel to and spaced from said first fish plate, and means extending through said tongues for maintaining the separable fish plate in position.

2. A rail joint including a bridge piece 35 having the top thereof of a contour of the head of a rail and said bridge piece adapted to be interposed between the ends of a pair of rails, a pair of fish plates integral with one side of said bridge piece and adapted to 40 be positioned at the sides of the web of a track rail, a fish plate integral with the other side of said bridge piece and adapted to be positioned one side of the web of the 45 other rail, and a fish plate detachably connected to said bridge piece and adapted to be positioned against the other side of the web of the other rail.

3. A rail joint comprising a bridge piece having one side provided with a stepped extension and a plurality of tongues, a fish plate abutting against said extension and mounted upon said tongues, means extending through the tongues for detachably connecting said fish plate to said bridge piece, 50 a pair of oppositely disposed fish plates integral with said bridge piece, and a fish plate integral with said stepped extension, said bridge piece having the upper portion 55 thereof conforming in contour to the head of a rail and adapted to be interposed between the ends of a pair of rails.

In testimony whereof I affix my signature in the presence of two witnesses.

HECTOR G. EVANS.
